UNITED STATES PATENT OFFICE

153,874

DESIGN FOR A TEXTILE FABRIC

Bernard J. Greenbaum, Weston, Conn.

Application June 22, 1948, Serial No. 147,117

Term of patent 3½ years

(Cl. D92—1)

To all whom it may concern:

Be it known that I, Bernard J. Greenbaum, a citizen of the United States of America and a resident of Weston, Fairfield County, State of Connecticut, have invented a new, original, and ornamental Design for a Textile Fabric, of which the following is a specification, reference being had to the accompanying drawing, forming part thereof.

The figure is a plan view of the fabric, showing my new design.

Said figure represents substantially one unit of the design, which unit repeats horizontally and vertically.

I claim:

The ornamental design for a textile fabric, as shown and described.

BERNARD J. GREENBAUM.
